SPREADER

Christian M. Harvey, Cleburne, Tex.

Application February 19, 1940, Serial No. 319,721

4 Claims. (Cl. 275—2)

This invention relates to a spreader and has particular relation to a machine for spreading sand and loose earth.

In building concrete highways it is now common practice to cover the road base, after it has been saturated with water, with a coating of asphalt and to cover the asphalt with a layer of sand. The plastic concrete of the roadway is then laid over the sand. The road bed as thus formed will retain the moisture which will prevent the bed from cracking in dry weather. It is one of the objects of the present invention to provide a sand spreader whereby the sand may be spread over the asphalt layer the full width of the roadway base and at a uniform thickness.

It is another object of the invention to provide a spreading machine of the character described forming a complete unit in itself which may be readily hitched to the truck supplying the sand and moved by said truck along the roadway while the sand is being delivered from the truck to the hopper of the spreader.

It is also common practice to cover the concrete roadway, immediately upon the laying thereof, with loose earth, of the required thickness, while the concrete sets and before the road is opened to traffic. In other words, the concrete is cured while covered with earth. It is another object of the present invention to provide a machine that may also be used for covering the green concrete roadway with a uniform layer of earth to protect the concrete until the same has set.

With the above and other objects in view the invention has particular relation to certain novel features of construction, operation and arrangement of parts, an example of which is given in this specification and illustrated in the accompanying drawings, wherein:

Figure 1 shows a side view of the type of machine specially designed for spreading sand shown hitched to a truck and partly in section.

Figure 2 shows a plan view thereof.

Figure 3 shows an enlarged, fragmentary, plan view thereof.

Figure 4 shows an enlarged, fragmentary, sectional view taken on the line 4—4 of Figure 3.

Figure 5 shows an enlarged, fragmentary, cross-sectional view taken on the line 5—5 of Figure 3.

Figure 6 shows an enlarged, fragmentary, plan view showing the delivery conveyor specially designed for conveying and distributing earth.

Figure 7 shows a side elevation thereof partly in section.

Figure 8 shows a cross-sectional view taken on the line 8—8 of Figure 6.

Figure 9 shows a plan view of a complete machine designed for the delivery of earth, and

Figure 10 shows a side elevation thereof.

Referring now more particularly to the drawings wherein like numerals of reference designate the same parts in each of the figures, the numerals 1, 1 designate side members of the carriage of the sand delivery machine which is supported on front and rear wheels 2 and 3. On this carriage there is mounted a motor 4 having a forwardly extended drive shaft 5. Mounted on the forward end of said carriage there is a receiving hopper 6 having a relatively lower front wall as shown in Figures 1 and 5 so as to readily receive sand from dump body 8 of truck 9 to which said carriage is coupled and by means of which the machine is moved along the roadway. As the sand is gradually unloaded from the truck body said body may be elevated by a conventional elevating means 9a so as to gradually discharge the sand into the hopper 6 as the machine moves along.

Mounted on the side members of the carriage and extending laterally underneath the hopper 6 there is a chute designated generally by the numeral 10 and which extends out a sufficient distance to span a roadway 11 as more clearly shown in Figure 2. This chute has side members 10a, 10b. The side member 10a extends up above the level of the upper margin of the side member 10b. This is illustrated more accurately in Figure 4 and also in Figure 8. The outer ends of the side members 10a, 10b are anchored to a suitable bracket 12 which is provided with a spindle 13 on which a carrier wheel 14 is mounted to rotate. The chute 10 is maintained in transverse relation with the carriage by means of a cable 15 which is attached at one end to the forward end of the truck and at its other end to the forward side of the bracket 12.

Fastened to the outer sides of the side members 1, 1 preferably by welding, are pairs of brackets 16, 16 and 17, 17 provided with horizontal bearings 18, 18 and 19, 19, respectively. The chute, as is obvious, may extend out in either direction from the carriage. In the present illustration it is shown extended outwardly to the right and the side members 10a, 10b are pivotally attached to the brackets 16 by means of spindles 20, 20 which are extended through the bearings 18, 18 and through corresponding bearings in the adjacent ends of the side members 10a, 10b as is clearly shown in Figure 4. On opposite sides of the hopper there are upstanding transverse guides 21, 21 which are fastened to the side members 1, 1 and

which are in substantial alignment with the corresponding side members 10a, 10b.

Mounted in the bearings 19 is a transverse shaft 22 and fixed on said shaft between said bearings is drum 23. The rear end of said shaft 22 is extended and fixed on said extended end are sprocket wheels 24, 25. Fixed on the forward end of the shaft 5 is a sprocket wheel 26 which is aligned with the sprocket wheel 25 and operating over these aligned sprocket wheels and transmitting rotation from the former to the latter there is a sprocket chain 27. At the outer end of the chute 10 there is a drum, similar to the drum 28 in Figure 7 and which is fixed on a shaft as 29 which is rotatable in suitable transversely aligned bearings in the side members of the chute. Fixed on one end of said shaft 29 there is a sprocket wheel 30 which is aligned with the sprocket wheel 24 and operating over these aligned sprocket wheels there is a sprocket chain 31 which transmits rotation to said sprocket 30 and to the drum 28. Operating over the drums 23 and 28, as shown in Figures 2 and 3 there is an endless conveyor belt 32 which travels between the side members 21, 21 and the aligned side members 10a, 10b. This belt is driven by the drums 23, 28. The upper run of the conveyor belt 32 is supported by a series of transverse rollers 34 mounted between the side members 21, 21 and 10a, 10b, as clearly shown in Figures 3 and 4. The return run of the belt 32 is supported against sagging by means of shoes, such as 35, 35 as shown in Figure 7 which are swung from the side members of the chute 10. The sand will be delivered as required into the hopper 6 and will fall down onto the conveyor belt 32 and will be continuously moved along the chute 10 while the spreader is moving forwardly at the required speed.

The chute 10 has a series of deflectors 36. The forward ends of these deflectors are anchored to the side member 10b of the chute. They are spaced apart along the chute and diverge forwardly with respect to the line of travel of the conveyor belt 32. They are blade-like in shape as illustrated in Figures 3 and 4. They extend rearwardly from the side member 10b, each deflector extending rearwardly the required distance further than the deflector behind it. The inner ends of the deflectors are anchored to a diagonal bar 37 whose forward end is fastened to the inner end of the side member 10b and whose rear end is fastened to the side member 10a. The lower margins of the deflectors 36 are closely adjacent the upper run of the conveyor belt 32. This upper run of the conveyor belt is on a level with the upper margin of the side member 10b. As the sand is moved outwardly along the belt 32 it will be deflected by the deflectors 36 and will pass through between said deflectors throughout the length of the chute 10 and will be distributed at a uniform thickness over the roadway throughout the width of said roadway.

When the load of sand in the truck body 8 has been exhausted the truck may be detached from the spreader and a loaded truck hitched to the spreader and its load gradually discharged into the hopper 6 as the spreader is moved along under the power of the truck connected to it. The work of spreading the sand may thus proceed in a substantially continuous manner.

A slightly modified form of spreader is desirable for covering a green concrete roadway with earth. For this purpose the earth will be plowed up along side the roadway and conveyed onto the concrete road thus at the same time forming the

road ditches. For this purpose the spreading apparatus may be mounted on a conventional type of road grading machine such as is illustrated in Figures 9 and 10 and which has an arched type carriage 38 supported by rear carrier wheel's 39, 39 and hitched to a tractor 40 usually of the caterpillar type. Secured to one side member of the carriage are vertical standards 41, 41 which are preferably formed of angle iron as shown in Figure 8. A supporting rod 42 is securely anchored at its ends to the carriage 38. The lower ends of the standards 41 are supported by this rod and are provided with notches where-in the rod is seated. The rod has one or more turn buckles as 43 for regulating its tension. The chute extends out laterally from the grader carriage and has the side members 10a, 10b as in the form shown in Figure 2. Their inner ends are mounted on a transverse shaft 44 which is mounted in side bearings 45, 45 carried by the standards 41. At their outer ends the side members have suitable transversely aligned bearings to receive the shaft 29 which has the drum 28 fixed thereon between said members and one end of the shaft 29 has the sprocket wheel 30 fixed thereon. The outer end of the chute is supported by chains 46, 46 whose outer ends are connected thereto and whose inner upper ends may be wound about a shaft 47 rotatably mounted in suitable bearings in side members 48, 48 of the top frame mounted on the main carriage 38. The rear end of the shaft 47 has a hand wheel 49 accessible to the operator whereby the shaft 47 may be rotated and the elevation of the chute regulated and thus maintained at the desired elevation above the paving. The shaft 47 may be held against backward rotation by a conventional rack and dog arrangement commonly used for the purpose but not shown.

The chute shown in Figure 7 is also equipped with the diagonal deflectors 36 whose forward ends are suitably secured to the side member 10b and whose rear ends are anchored to the diagonal brace 37 as hereinabove explained.

There is a supplemental frame composed of side members 10c, 10c whose upper inner ends are provided with bearings through which the shaft 44 extends thus providing a pivotal mounting for the supplemental frame. The outer ends of the side members 10c have aligned bearings 50, 50 to receive a transverse shaft 51 and fixed on this shaft between the side members 10c is drum 52. Fixed on the shaft 44 between the side members 10c, 10c there is a drum 53. An endless conveyor belt 54 is mounted to travel around the drums 28, 52 and 53 and the return run of this belt is supported by a transverse roller 55a which is fixed on shaft 55 mounted to rotate in transversely aligned bearings 56 which are fixed on the standards 41 and the return run of said belt is also supported by the shoes 35, 35 all of which is shown in Figure 7. The supplemental frame of the side members 10c is supported, and may be elevated and lowered, by chains 57, 57 whose lower ends are connected to said side members and whose upper ends are wound about a longitudinal shaft 58 rotatable in suitable bearings in the side members 48 of the top frame. A hand wheel 59, accessible to the operator, is fixed on the rear end of the shaft 58. The receiving end of the conveyor belt 54 may therefore be elevated and lowered into the desired relation with the ground surface. The shaft 58 may be held against reverse rotation by means of a suitable

conventional rack and dog arrangement provided for the purpose.

In this form the rear end of the shaft 44 is extended and fixed on said extended end are sprocket wheels 60, 61, the latter of which is aligned with the sprocket wheel 30 and a sprocket chain 62 operates over the sprocket wheels 61, 30 and transmits rotation from the former to the latter. The sprocket wheel 60 is driven by a sprocket chain 63 which operates thereover and which in turn is driven by a sprocket wheel 64 on the shaft 5a of the motor 4. Through the gearing described the belt or apron 54 may be driven.

The grading machine is equipped with a conventional disc plow 65 which is set at a forwardly diverging angle relative to the line of travel of the machine. This disc forms a furrow and throws the earth onto the adjacent lower end of the belt 54 and the earth is carried up along the upper run of the belt and is successively engaged by the deflectors 36 and spread over the green concrete of the roadway at a uniform thickness throughout the length of the chute.

Means have been provided for evenly distributing the earth over the belt 54 before it reaches the deflectors 36. For this purpose there are upstanding standards 66, 66 secured to the side members 10c, 10c and mounted in suitable transversely aligned bearings in said standards there is a transverse shaft 67, one end of which is extended and has a gear wheel 68 fixed thereon in mesh with and driven by a corresponding gear wheel 69 fixed on the shaft 44, and whereby rotation is imparted to the shaft 67. This shaft has radial blade-like arms 71, 71 thereon. These arms are pitched in a direction to spread the earth each way from the central line of the belt 54. The earth thrown by the disc 65 will be thrown onto the center of the belt 54 in a ridge which will be distributed to a uniform depth across the belt so that as the earth is deflected by the deflectors 36 it will be distributed onto the paving beneath uniformly.

Usually the chute of the form shown in Figures 6 and 7 will be of a length to extend only to a point about midway of the paving so that only one side of the paving will be covered while the machine is operating on one side of the road. Thereafter, the machine may be transferred to the other side of the highway and operated in the other direction and the other side of the paving then covered.

The drawings and description are illustrative merely, while the broad principle of the invention will be defined by the appended claims.

What I claim is:

1. A spreader for earth material comprising a carriage, a laterally extended chute on the carriage including an endless conveyor belt, means for driving the belt to convey the earth material thereon toward the end of the chute, a single series of deflectors on the chute above the belt which are effective to discharge said material conveyed by the belt laterally from the chute, the deflectors diverging forwardly from the line of travel of the belt.

2. A spreader for earth material comprising a

carriage, a frame extending laterally from the carriage, means for delivering said material to the frame, an endless conveyor belt on the frame to receive said material, a distributor arranged to distribute the material uniformly across the belt from one margin to the other margin thereof, deflectors extending over the belt in front of the distributor and engageable with the material carried by the belt to discharge the material laterally from the belt, the deflectors extending over the belt varying distances whereby said lateral discharge of the material is substantially the same throughout the length of the frame.

3. A spreader for earth material comprising a carriage, a chute extended laterally from the carriage and having upstanding side members one of which extends up above the level of the upper margin of the other, an endless conveyor belt mounted to travel between the side members of the chute, means for driving the belt to convey earth material thereon from one end toward the other, or discharge, end of the chute, a diagonal bar one end of which is anchored to the side member of the lower level, said bar diverging from said last mentioned side member toward the discharge end of the chute and having its other end anchored to the other side member, a series of deflectors above the belt which are anchored, at one end, to said bar and which diverge forwardly therefrom and whose other ends are anchored to the side member of the lower level, said deflectors being arranged with their lower margins adjacent the belt and gradually increasing in length toward the discharge end of the chute whereby the material on the belt will be gradually discharged over the side member of the lower level in substantially a uniform sheet along said chute.

4. A spreader for earth material comprising a carriage, a chute extended laterally from the carriage and having upstanding side members one of which extends up above the level of the upper margin of the other, an endless conveyor belt mounted to travel between the side members of the chute, means for driving the belt to convey earth material thereon from one end toward the other, or discharge, end of the chute, a diagonal bar one end of which is anchored to the side member of the lower level, said bar diverging from said last mentioned side member toward the discharge end of the chute and having its other end anchored to the other side member, a single series of deflectors above the belt which are anchored, at one end, to said bar and which diverge forwardly therefrom and whose other ends are anchored to the side member of the lower level, said deflectors being arranged with their lower margins adjacent the belt and gradually increasing in length toward the discharge end of the chute, whereby the material on the belt will be gradually discharged over the side member of the lower level in substantially a uniform sheet along the chute, and a distributor arranged in advance of the deflectors for distributing the material uniformly across the belt from one margin to the other margin thereof.

CHRISTIAN M. HARVEY.
